(57) **CLAIM**

The ornamental design for the dispensing gun for dispensing flowable product from a pressurized can, as shown and described.

DESCRIPTION

FIG. 1 is a front perspective of a dispensing gun for dispensing flowable product from a pressurized can showing our new design together with broken lines depicting a pressurized can.

FIG. 2 is a front elevational view thereof.

FIG. 3 is a right elevational view thereof.

FIG. 4 is a top plan view thereof.

FIG. 5 is a rear elevational view thereof.

FIG. 6 is a left elevational view thereof; and,

FIG. 7 is a bottom plan view thereof.

Portions drawn in broken lines are for illustrative purposes only and form no part of the claimed design.

1 Claim, 7 Drawing Sheets
